UNITED STATES PATENT OFFICE.

BURNHAM C. STICKNEY, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

Application filed November 30, 1921. Serial No. 518,810.

To all whom it may concern:

Be it known that I, BURNHAM C. STICKNEY, a citizen of the United States, residing in Elizabeth, in the county of Union and State of New Jersey, have invented certain new and useful Improvements in Combined Typewriting and Computing Machines, of which the following is a specification.

This invention relates to combined type-writing and computing machines, and is herein illustrated as applied to a bookkeeping machine of the Underwood-Hanson type.

In machines of the type referred to, depression of the numeral keys effects step-by-step movement of the carriage in a letter-feeding direction, and the carriage, in passing through a computing zone, acts through a suitable transposition mechanism to so position seriatim denominational bars having index-pins thereon as to permit digits to be indexed in the different denominations in accordance with the numeral keys depressed. The pin-setting mechanism is actuated each time a numeral key is depressed, but no indexing is effected unless a denominational or pin bar has been selected by the carriage acting through a suitable transposition mechanism. When the different digits of a number have been indexed as described, a general operator is actuated to move the pin-bars in accordance with the setting of the index-pins and the corresponding number is added into the register.

The main object of the present invention is to provide improved transposition mechanism, simple in construction and certain in action.

According to the present embodiment of the invention, the effective path of the denomination-selector tappets is adjacent the rear ends of the pin-bars, and, as the movement of the tappet for each letter-space movement of the carriage may be determined as desired, independent actuation of the different pin-bars may be effected with greater certainty than in the usual form of machine, in which the denominational jacks are at letter-space distances apart and the supporting end of each jack or dog is so small that great care must be taken to main-

tain the parts in close adjustment to insure correct operation.

The tappets or cam members are pivotally mounted on the selectors, so that, when moved past the pin-bars in letter-feeding movement of the carriage, movement of the tappets about their pivots will be prevented and the various pin-bars will be cammed forward in succession, but, when the carriage is moved in the opposite direction, the tappets, upon engagement with the ends of the pin-bars, will be swung about their pivots to ineffective position and will pass idly the ends of the pin-bars. The selectors, with the tappets thereon, may be adjustably mounted on a continuous band, preferably of steel, which may be carried by sprocket-wheels, one at each side of the machine, said sprocket-wheels having pins or teeth mounted thereon at regular intervals and projecting through suitable openings in the band as the latter is fed therearound. To drive the band, provision may be made of a pinion fixed to one of the sprocket-wheels and a rack mounted on the carriage and normally meshing with the pinion. It should be understood that the relation between the diameters of the pinion and the associated sprocket-wheel is such that a letter-space movement of the carriage will effect a movement of a tappet on the lower stretch of the band sufficient to carry it from effective engagement with one of the pin-bars to effective engagement with the next.

To secure the selectors on the band, the latter is provided, at intervals corresponding to the distances between the rear ends of successive pin-bars, with perforations, and the selectors are provided with slots to receive the band and with openings on the opposite sides of the slot, which may be brought into register with one of the perforations in the band by engagement of wedge-shaped portions of the selectors with notches in the forward edge of the band. When placed in adjusted position, each selector may be secured to the band by a screw passing through the aligned openings in the band and the selector.

To prevent improper displacement of the tappets when brought into engagement with the pin-bars, provision may be made of

guiding means to support both the lower stretch of the band and the selectors thereon.

Provision may be made of more than one register, and, consequently, of more than one set of pin-bars. When this is the case, the rear ends of the different sets of pin-bars are displaced vertically with reference to each other, and the tappets are arranged 10 at different heights on the selectors, so that each selector will engage only the pin-bars in the corresponding set.

Provision may be made of a non-compute key at the front of the machine and of a 15 device operable thereby to shift the ends of the pin-bars out of alignment with the tappets, so that no denomination selecting will be effected when the carriage passes through a computing zone.

20 When the selectors are to be set in adjusted position on said band, the pinion connected with one of the sprocket-wheels is disconnected from the carriage and the portion of the band on which the selectors 25 are to be placed is brought into the upper stretch adjacent to a fixed scale which indicates the distance at which the selectors for the different sets of pin-bars are to be positioned. The band may be provided with 30 markings corresponding to those on the usual letter-space scale to assist in positioning the selectors. When the selectors are suitably positioned on the band, the latter is restored to its normal position with 35 reference to the carriage and the connection between the carriage and band restored. To enable such connection and disconnection to be effected, the rack may be hinged to the carriage to enable it to be swung out 40 of position to mesh with the pinion with which it usually co-operates.

It will be seen that, according to the present invention, lost motion in the transposition mechanism is to a great extent 45 eliminated.

Other features and advantages will hereinafter appear.

In the accompanying drawings,

50 Figure 1 is a diagrammatic side elevation, partly in section, showing the invention applied to an Underwood-Hanson book-keeping machine.

Figure 2 is a front elevation of the transposition mechanism.

55 Figure 3 is a plan view of a portion of the mechanism shown in Figure 2.

Figure 4 is a detail view of a portion of the band carrying the denomination-selectors and of the scale-plate provided 60 with markings to assist in obtaining the proper relative positions of selectors for use with the different registers.

Depression of numeral keys 11 and alpha- 65 bet keys 12 will actuate key-levers 13 and bell-crank 14 to swing type-bars 15 up-

wardly and rearwardly to effect typing, by means of types 16 thereon, on work-sheets supported on a platen 17. The platen 17 is mounted for rotation in a platen-frame 18 mounted in a carriage 19 which is supported at its rear for movement transversely of the machine on a rail 20.

The carriage 19 is normally urged to the left by means, not shown, and is normally restrained from such movement by means of a rack 21 connected to the carriage and meshing with a pinion 22 having a one-way connection with an escapement wheel 23. As an actuated type-bar 15 nears the end of its effective stroke, the heel 24 thereon will engage a universal frame 25 and operate a rocker 26 carrying the usual fast and loose dogs 27 and 28, respectively, thereby permitting letter-feeding movement of the escapement wheel 23 and consequently 85 of the carriage 19.

Each time a numeral key is depressed to print a significant digit, a pin or link 29 connected therewith engages an arm 30 on a shaft 31 of a set corresponding in number to the significant numeral keys and actuates a linkage 32 to depress a pin-setting bar 33 thereof. The index-pins 34, which are carried by the denominational or pin-bars 35, are normally out of alignment with the bars 33, and, except when a pin-bar is selected and advanced by the carriage by means to be described hereinafter, none of the pins 34 will be set upon depression of the bars 33. Upon completion of the indexing of a number, by depressing suitable pins 34 on the pin-bars of a set, a shaft 36 may be rotated in a counterclockwise direction, as seen in Figure 1, by means of a handle (not shown), and this motion may be transmitted, by means of toothed sectors 37, fixed on the shaft 36, to pinions 38, which mesh with racks 39, forming parts of a general operator 40, thereby effecting 100 forward movement of the latter.

In such forward movement of the general operator, a bar 41 thereon will engage the lower ends of depressed pins 34, and advance the pin-bars 35, in accordance with the pins depressed, and, consequently, in accordance with the digits indexed. The pin-bars 35 have one-way driving connections with number-wheels 42, such connections including racks 43 on the bars 35, and, upon forward movement of the bars 35, the 115 number-wheels 42 will be turned in accordance with the digits indexed, the result of the operation being read through a sight-opening 44 in a computer-casing 45.

Provision may be made at the rear of the carriage of rearwardly-extending arms 46, carrying a rack-bar 47, on which may be set, at letter-space intervals, tabulator-stops 48, with which vertically-movable plungers or counter-stops 49 may cooperate when raised 120

by tabulator-keys (not shown). The arms 46 may be extended rearwardly to support a portion of the transposition mechanism, through which the denomination-selecting 5 of the pin-bars 35 is effected. Provision may be made of hinge members 50, secured to the extension of the arms 46, by means of screws 51, and these hinge members 50 may include hinge pins 52, around which extend 10 portions 53 of a frame 54, having at its lower edge a rack 55. The rack 55 is normally in operative engagement with a pinion 56, so as to drive the same during movement of the carriage 19 in either direction. 15 The arrows on Figure 2 indicate the direction of rotation of wheels 65 and 69 during letter-feed movements of the carriage.

To maintain the rack 55 in effective engagement with the pinion 56, provision may 20 be made of a fixed arm 57, extending downwardly at the end of the rack adjacent one end of the carriage, and this arm may be engagement with the pinion 56, provision may opening 59 in the rack end is in alignment 25 when the rack is in effective position, this alignment being maintained by a pin 60 normally extending through said openings 58 and 59. The pin 60 may normally be held in effective position by means of a leaf- 30 spring 61 engaging in a groove 62 of the pin 60, and the pin 60 may be withdrawn from latching relation by means of a head 63 thereon, the rack then being released to enable movement thereof out of engagement 35 with the pinion 56, for a purpose to be described hereinafter. Upon movement of the rack out of effective position and release of the head 63, the pin 60 will return to normal position and prevent return of the rack 40 55 to effective position.

The pinion 56 is fixed to a hub 64, to which is also fixed a toothed wheel or sprocket-wheel 65, having beveled teeth 66 engaging in openings 67 in a continuous 45 band 68, extending around the toothed wheel 65 at one side of the typewriter-frame and a corresponding toothed wheel 69 at the other side of the typewriter-frame. To support the hub 64, provision is made of a boss 50 70 held on the typewriter-frame by suitable means, such as screws 70^a, and a pin 71 is passed through the hub 64, a reduced portion 72 of the pin being fitted into an opening in the boss 70 and secured therein by means of 55 a set-screw 73. At its outer end, the pin 71 is provided with an enlarged head 74, which serves to retain the hub 64 on the pin, and a shoulder 75, formed between the main portion of the pin 71 and its reduced portion 60 72, is at a distance from the head 74 sufficient to receive the hub 64, and to determine the proper position of the reduced portion 72 in the boss 70. The hub 64 of the wheel 69 may be supported by a boss 70 fixed 65 on the typewriter-frame on the side oppo-

site that on which the first-mentioned boss 70 is mounted.

It will be seen that the upper stretch of the band 68 will move in the same direction as the carriage when the rack 55 is in engagement with the pinion 56, and that the lower stretch of the band moves in the opposite direction. The selection of the pin-bars 35 in the proper order may then be obtained by means of selectors 76, which, in moving along the lower stretch, will cause tappets or dogs 77 thereon to engage rearward extension 78 of pin-bars 35, to advance the same seriatim, to enable setting of the pins 34 by means of the pin-setting linkages. The dogs or tappets 77 may be so mounted on the selectors 76 that, in passing the corresponding extensions 78 of the pin-bars, as the carriage moves in a letter-feeding direction, they will be maintained in effective position on the selectors, but, when moved in the opposite direction past the extensions 78, they will yield, and no advancing of the extensions 78 will be effected. The tappets 77 may be mounted on 90 the selectors 76 in substantially the same manner as the tappets are mounted in the selectors ordinarily in use in the Underwood-Hanson bookkeeping machines.

As herein disclosed, the machine is 95 equipped with three registers, each of which includes a set of the number-wheels 42. In order that computations may be effected independently in the different registers, the rearward extensions of the different sets of pin-bars 35 are arranged in different horizontal planes, as shown in Figure 1, the extensions of the right-hand set being lower than those of the middle set, and the extensions of the middle set being lower than those of the left-hand set. It will be evident that, by arranging the tappets on different selectors at the proper heights, the set of extensions 78 upon which each selector will be effective can be determined. 100

The extensions 78 of the pin-bars 35 may be guided near the rear ends of the body-portions of the pin-bars 35 by a slotted member 79. The bottoms of the slots for the various extensions 78 may be positioned so that the extensions 78 will be supported thereby in the position shown in Figure 1. In order to prevent lateral deflection of the extensions 78 when engaged by the tappets 77, each set of extensions 78 may be guided 115 in a slotted member 80 suitably supported on the rear of the computer-casing.

Each of the selectors 76 may comprise a vertical portion in which a tappet 77 is mounted and a horizontal portion or extension 76^a having a slot 76^b therein to receive the band 68. At the bottom of each of the slots 76^b the selector may be provided with a beveled portion 81 adapted to seat itself in notches 82 in the forward edge 120 125 130

of the band 68, these notches being spaced at the same distance as the extensions 78 of each set of pin-bars, which is the same as the length of step movement of a selector 5 for each letter-space movement of the carriage. The pin-bars 35 are formed or spread out at their rear ends, and the pinion 56 is so proportioned with reference to the toothed wheels 65 and 69 that a selector on 10 the band 68 will be moved the proper distance at each letter-space movement of the carriage.

After positioning the selector 76 by means of a notch 82, the selector is held in position 15 by passing a screw 83 through an opening 84 in the band 68 and aligned openings on the opposite sides of the slot 76^a, one of said openings 84 being provided opposite each of the notches 82. The screw 83 is provided 20 with a knurled head 85 for manipulating the same, and is threaded into the selector preferably on the side of the slot 76^a opposite the head 85. It should be understood that the horizontal portion 76^a of 25 each selector 76 does not extend to the rear far enough to interfere with passage of the band 68 around the toothed wheels 65 and 69.

In order to insure proper positioning of 30 the selectors as they are carried past the extensions 78 of the pin-bars 35, provision is made of suitable guiding means for both the band 68 and the selectors. This may comprise a guide 86 extending across the 35 rear of the computer-casing and supported by each of its ends on the latter by means of a bracket 87. The guide 86 is provided with a slot 88 to receive the horizontal portion of each of the selectors. Since the rear 40 end of the selector engages the rear end of the slot, rearward movement of the selector will be prevented, and since each of the extensions 76^a is rectangular in section and of sufficient width, the rocking of the selector 45 about the axis of the horizontal portion 76^a will be prevented. The guide 86 is also provided with a slot 89 extending rearwardly from the slot 88, and of suitable size to receive the portion of the band lying to 50 the rear of the portion which may be embraced by the selectors. It will be evident that by this arrangement proper positioning of the tappets as they are carried past the extensions 78 will be assured.

55 As hereinbefore described, by moving the rack 55 rearwardly out of engagement with the pinion 56, the carriage may be disconnected from the transposition mechanism. This manner of disconnection is utilized in 60 connection with setting the selectors 76 on the band 68, the portion of the belt 68 on which the selector or selectors are to be set being brought into the upper stretch of the band extending between the toothed wheels 65 and 69, and the selectors set by means

of the proper notches in the band 68. If desired, the band 68 may be supplied with indications to assist in positioning the selectors.

If computation is to be effected in all of the registers simultaneously, the selectors for any two sets must be set apart a distance corresponding to the distance between corresponding sets of pin-bars. This positioning may be conveniently obtained by means of a scale 90 overlying the upper stretch of the band centrally of the machine, and provided with indications marked "R1", "R2" and "R3", which correspond to the registers 70 taken in order from left to right at the front of the machine. As shown in Figure 4, the selectors may be marked with numerals to indicate which one of the registers, numbered from left to right at the front of 75 the machine, is to be actuated thereby. The indications on the band corresponding to letter-space positions of the carriage are shown in Figure 4, and numbers corresponding to the letter-space positions are marked 80 on the band. To support the scale 90, provision may be made of a bracket 91 formed from the same piece of sheet-metal as the scale. The bracket 91 may be bent upwardly from the rear of the scale and then forwardly to enable an upturned portion at the end of the forward extension to be secured to the tabulator bracket by means of a screw 92. After the selectors 76 have been 85 set on the band 68, the latter may be brought into proper relation with the carriage by bringing a mark on the band into alignment with a mark on the scale 90, and the rack 90 may be brought into mesh with the pinion 55. 90

100 Provision may also be made whereby, upon rearward movement of a non-compute key 93, the rearward extensions 78 of the pin-bars 35 will be moved out of the path of the tappets 77. To this end, provision is made of a rod 94 extending beneath the pin-bars 35 near the member 79, and supported by means of arms 95 fixed on a shaft 96. Upon rearward movement of the non-compute key 93, a link 97 fixed 105 thereto and pivoted to the forward end of link 98 will move the latter rearwardly, and, by means of an arm 99 pivoted to the rear end of the link 98 and fixed on the shaft 96, will rock the latter, thereby swinging the rod 94 forwardly to lift the rear ends of the pin-bars 35 sufficiently to move the extensions 78 out of the paths of the corresponding tappets. When the non-compute key 93 reaches its rearward position, a pin 100, extending laterally from the link 98 and riding in the horizontal portion of a slot 101 in an adjacent member, will drop 110 into the vertical portion 102 of the slot, and the non-compute key will be retained 115 120 125 130

in its rearward position until the pin 100 is lifted out of the vertical portion 102 of the slot either manually or upon operation of the general operator. The mechanism 5 for lifting the pin 100 out of the vertical portion 102 of the slot may be of the usual type found in the Underwood-Hanson machines.

Variations may be resorted to within the 10 scope of the invention, and portions of the improvements may be used without others.

Having thus described my invention, I claim:

1. In a combined typewriting and computing machine, in combination, a traveling carriage in the upper part of the machine, having a letter-feed movement from right to left, a register comprising a set of numeral wheels, mechanism for operating said 15 wheels, including a series of denominational members arranged in descending order from left to right, index devices on each of said members, and carriage-actuated means to shift said denominational members seriatim 20 to enable setting of the index devices thereon, including a flexible band guided in a straight line adjacent said members and moving past the same from left to right during a letter-feed movement of the carriage, and a tappet on said band to engage and actuate said members as the carriage passes step-by-step through a computing zone.
2. In a combined typewriting and computing machine, in combination, a traveling carriage in the upper part of the machine, having a letter-feed movement from right to left, a register comprising a set of numeral wheels, mechanism for operating said wheels, 25 including a series of denominational members arranged in descending order from left to right, index devices on said members, carriage-actuated means to shift said denominational members seriatim to enable setting 30 of the index devices thereon, including a flexible band guided in a straight line adjacent said members and moving past the same from left to right during a letter-feed movement of the carriage, a tappet on said band to engage and actuate said members as the carriage passes step-by-step in a letter-feed direction through a computing zone, and non-compute means to move said denominational members out of the effective path 35 of said tappet.
3. In a combined typewriting and computing machine, in combination, a carriage having letter-feed movements in one direction, a set of number wheels, denominational 40 bars by which actuation of said wheels is controlled, a cam element adapted to actuate said bars seriatim when moved in the reverse of the letter-feed direction, and carriage-actuated means to move said element, comprising a continuous band having one 45 stretch thereof adjacent the rear ends of said bars, said cam element and said band having co-operating means whereby the cam element may be secured on said band at intervals corresponding to the spacing of 70 the denominational bars.
4. In a combined typewriting and computing machine, in combination, a carriage having letter-feed movements in one direction, a set of number-wheels, denominational 75 bars by which actuation of said wheels is controlled, a cam element adapted to actuate said bars seriatim when moved in the reverse of the letter-feed direction, and carriage-actuated means to move said cam element, 80 comprising a continuous band having one stretch thereof adjacent the rear ends of said bars, said band having perforations at intervals corresponding to the distances between the rear ends of said bars, said cam element having a slotted portion to receive said band and openings in alignment on opposite sides of the slot, and a securing member to pass through the openings in said cam element and one of said perforations in the band to hold said cam element in 85 adjusted position.
5. In a combined typewriting and computing machine, in combination, a carriage having a letter-feed movement in one direction, a set of number wheels, denominational bars by which actuation of said wheels is controlled, a cam element adapted to actuate said bars seriatim when moved in the reverse of the letter-feed direction, carriage-actuated means to move said cam element, 90 comprising a continuous band having one stretch thereof adjacent the rear ends of said bars, said band having perforations at intervals corresponding to the distances between the rear ends of said bars, said cam element having a slot therein to receive said band and openings in alignment on opposite sides of the slot, and a securing member to pass through the openings in said cam element and one of said perforations in the band to hold said cam element in 95 adjusted position.
6. In a combined typewriting and computing machine, in combination, a carriage having a letter-feed movement in one direction, a set of number wheels, denominational bars by which actuation of said wheels is controlled, a cam element adapted to actuate said bars seriatim when moved in the reverse of the letter-feed direction, carriage-actuated means to move said cam element, comprising a continuous band having one stretch thereof 100 adjacent the rear ends of said bars, said band having perforations at intervals corresponding to the distances between the rear ends of said bars, said cam element having a slot therein to receive said band and openings in alignment on opposite sides of the slot, and a securing member to pass through the openings in said cam element and one of said perforations in the band to hold said cam element in 105 adjusted position on the band, and guiding means for said band to insure the proper positioning thereof adjacent said bars.
7. In a combined typewriting and computing machine, in combination, a carriage having a letter-feed movement in one direction, a set of number wheels, denominational bars by which actuation of said wheels is controlled, a cam element adapted to actuate said bars seriatim when moved in the reverse of the letter-feed direction, carriage-actuated means to move said cam element, comprising a continuous band having one stretch thereof 110 adjacent the rear ends of said bars, said band having perforations at intervals corresponding to the distances between the rear ends of said bars, said cam element having a slot therein to receive said band and openings in alignment on opposite sides of the slot, and a securing member to pass through the openings in said cam element and one of said perforations in the band to hold said cam element in 115 adjusted position on the band, and guiding means for said band to insure the proper positioning thereof adjacent said bars.
8. In a combined typewriting and computing machine, in combination, a carriage having a letter-feed movement in one direction, a set of number wheels, denominational bars by which actuation of said wheels is controlled, a cam element adapted to actuate said bars seriatim when moved in the reverse of the letter-feed direction, carriage-actuated means to move said cam element, comprising a continuous band having one stretch thereof 120 adjacent the rear ends of said bars, said band having perforations at intervals corresponding to the distances between the rear ends of said bars, said cam element having a slot therein to receive said band and openings in 125

- alignment on opposite sides of the slot, and a securing member to pass through the openings in said cam element and one of said perforations in the band to hold said cam element in adjusted position on the band, and guiding means for said band to insure the proper positioning thereof adjacent said bars, and also for said cam element to assist in holding the same in proper position relative to said denominational bars.
7. In a combined typewriting and computing machine, in combination, a typewriter carriage, a register comprising numeral wheels, actuating means for said wheels including denominational elements actuatable in accordance with digits indexed thereon, a tappet to select the denominational elements seriatim and shift them to positions to receive such indexing, and a transposition device comprising an endless band having an upper stretch moving in the letter-feed direction and a lower stretch moving in the opposite direction adjacent said denominational elements.
- 15 8. In a combined typewriting and computing machine, in combination, a typewriter carriage, a register comprising numeral wheels, actuating means for said wheels including denominational elements actuatable in accordance with digits indexed thereon, a tappet to select the denominational elements seriatim and shift them to positions to receive the indexing of digits, and a transposition device comprising an endless band having a lower stretch adjacent said denominational elements and moving in the reverse of the letter-feed direction, band-carrying wheels having projections entering openings in the band, and a driving connection between said carriage and one of said wheels.
- 20 9. In a combined typewriting and computing machine, in combination, a typewriter carriage, a register comprising numeral wheels, actuating means for said wheels including denominational elements actuatable in accordance with digits indexed thereon, a tappet to select the denominational elements seriatim and shift them to positions to receive the indexing of digits, and a transposition device comprising an endless band having a lower stretch adjacent said denominational elements and moving in the reverse of the letter-feed direction, band-carrying wheels having projections entering openings in the band, and a driving connection between said carriage and one of said wheels, including a pinion fixed to the wheel and a rack attached to the carriage and meshing with the pinion.
- 25 10. In a combined typewriting and computing machine, in combination, a carriage, denominational devices on which digits may be indexed, and selecting means for determining the devices on which digits are to be indexed, including a tappet to co-operate with said devices, a selector block to carry said tappet, and a band on which said block may be set at intervals corresponding to the distances between said devices.
- 30 11. In a combined typewriting and computing machine, in combination, a carriage, denominational devices on which digits may be indexed, and selecting means for determining the devices on which digits are to be indexed, including a tappet to co-operate with said devices, a selector block to carry said tappet, a band on which said block may be set at intervals corresponding to the distances between said devices, said band having notches at intervals corresponding to the distances between said devices, and said block having a portion to co-operate with said notches in properly positioning the block, and means to secure said block in adjusted position on said band.
- 35 12. In a combined typewriting and computing machine, in combination, a carriage, denominational devices on which digits may be indexed, and denomination-selecting means to co-operate with said devices, comprising a selector to engage said devices, and transposition mechanism including an endless band on which said selector may be set at regular intervals corresponding to the spacing of said denominational devices, said band having a lower stretch along which the selector is moved to co-operate with said devices and an upper stretch to which any point of the band is brought when the selector is to be positioned thereat.
- 40 13. In a combined typewriting and computing machine, in combination, a carriage, denominational devices on which digits may be indexed, denomination-selecting means to co-operate with said devices, comprising a selector to engage said devices, transposition mechanism including an endless band on which said selector may be set at regular intervals corresponding to the spacing of said denominational devices, said band having a lower stretch along which the selector is moved to co-operate with said devices and an upper stretch to which any point of the band is brought when the selector is to be positioned thereat, and a scale adjacent the upper stretch of said band to assist in positioning the selector with reference to the carriage.
- 45 14. In a combined typewriting and computing machine, in combination, a carriage, a plurality of sets of denominational devices on which digits may be indexed, denomination-selecting means to co-operate with said devices, comprising selectors to engage respectively the devices of the different sets, transposition mechanism including an endless band on which said selectors may be set at intervals corresponding to the spacing of said denominational devices,
- 50 55 60 65 70 75 80 85 90 95 100 105 110 115 120 125

- said band having a lower stretch along which the selectors are moved to co-operate with said devices and an upper stretch to which any point of the band is brought when a selector is to be positioned thereat, and a scale to indicate the relative positions of the different selectors when denomination selecting is to be effected for all the sets of devices simultaneously.
- 10 15. In a combined typewriting and computing machine, in combination, a traveling carriage, a series of reciprocable denominational bars, transposition mechanism comprising a cam member mounted for movement past said bars in a path parallel to that of the carriage to engage said bars seriatim in a direction reverse of that of the carriage, said cam member being so shaped that in its movement in such reverse direction it will engage each of the bars and cam the same into a selected position, carriage-actuated means for moving said cam member in such reverse direction, and means for shifting the ends of the bars adjacent said cam member out of alignment therewith.
- 15 20 25 30 35 40 45 50 55 60 65 16. In a combined typewriting and computing machine, in combination, a traveling carriage, a series of reciprocal denominational bars, transposition mechanism comprising a cam member mounted for movement past said bars in a path parallel to that of the carriage to engage said bars seriatim in a direction reverse of that of the carriage, said cam member being so shaped that in its movement in such reverse direction it will engage each of the bars and cam the same into a selected position, carriage-actuated means for moving said cam member in such reverse direction, a member beneath said bars and extending transversely thereof, and manually-operable means for lifting said member and thereby shifting the adjacent ends of the bars out of alignment with said cam member.
16. In a combined typewriting and computing machine, in combination, a typewriter including a carriage, a computer casting on which said typewriter rests, a set of number wheels in the front part of said casting, denominational bars having sets of index-pins thereon, each having a one-way connection with the corresponding number wheel, means for indexing digits on said pins in accordance with digits typed, means for selecting the bars on which indexing is to be effected, comprising a cam member movable in the reverse of the letter-feed movement to engage said bars seriatim and advance them to indexing position, a rod extending transversely beneath said bars near their rear ends, a non-compute key at the front of said casting, and means whereby actuation of said key will effect a lifting of said rod and movement of the rear ends of said bars out of alignment with said cam member.
17. In a combined typewriting and computing machine, in combination, a carriage, numeral keys, numeral-key-actuated indexing devices, a plurality of sets of number-wheels, a set of denominational bars for each set of wheels, having an operative connection at their forwards ends with said number-wheels, the rear ends of the bars of the different sets lying in different horizontal planes, indexing pins on said bars and normally out of alignment with said indexing devices, denomination-selecting means to actuate the bars seriatim to enable the pins to be set, including selectors movable past the rear ends of the bars from left to right during the letter-feed movement of the carriage and tappets arranged on said selectors at heights corresponding to the heights of the rear ends of the bars of the different sets, and means to destroy the alignment between the tappets and the rear ends of the corresponding sets of denominational bars.
18. In a combined typewriting and computing machine, in combination, a carriage, numeral keys, numeral-key-actuated indexing devices, a plurality of sets of number-wheels, a set of denominational bars for each set of wheels, having an operative connection at their forwards ends with said number-wheels, the rear ends of the bars of the different sets lying in different horizontal planes, indexing pins on said bars and normally out of alignment with said indexing devices, denomination-selecting means to actuate the bars seriatim to enable the pins to be set, including selectors movable past the rear ends of the bars from left to right during the letter-feed movement of the carriage and tappets arranged on said selectors at heights corresponding to the heights of the rear ends of the bars of the different sets, and means to destroy the alignment between the tappets and the rear ends of the corresponding sets of denominational bars.
19. In a combined typewriting and computing machine, in combination, a carriage, numeral keys, numeral-key-actuated indexing devices, a plurality of sets of number-wheels, a set of denominational bars for each set of wheels, having an operative connection at their forward ends with said number-wheels, the rear ends of the bars of the different sets lying in different horizontal planes, indexing pins on said bars and normally out of alignment with said indexing devices, denomination-selecting means to actuate the bars seriatim to enable the pins to be set, including selectors movable past the rear ends of the bars from left to right during the letter-feed movement of the carriage and tappets arranged on said selectors at heights corresponding to the heights of the rear ends of the bars of the different sets, and means to destroy the alignment between the tappets and the rear ends of the corresponding sets of denominational bars.
20. In a combined typewriting and computing machine, in combination, a carriage, numeral keys, numeral-key-actuated indexing devices, a plurality of sets of number-wheels, a set of denominational bars for each set of wheels, having an operative connection at their forward ends with said number-wheels, the rear ends of the bars of the different sets lying in different horizontal planes, indexing pins on said bars and normally out of alignment with said indexing devices, denomination-selecting means to actuate the bars seriatim to enable the pins to be set, including selectors movable past the rear ends of the bars from left to right during the letter-feed movement of the carriage and tappets arranged on said selectors at heights corresponding to the heights of the rear ends of the bars of the different sets, and means to destroy the alignment between the tappets and the rear ends of the corresponding sets of denominational bars.

said selectors at heights corresponding to the heights of the rear ends of the bars of the different sets, a device adapted to lift the rear ends of all of said bars substantially simultaneously, and a manually-operable means for actuating said device.

21. In a combined typewriting and computing machine, in combination, a typewriter carriage, denominational elements, and carriage-actuated denomination-selecting means for actuating said denominational elements seriatim in the reverse of the letter-feed direction, comprising a selector to engage said elements, a carrier on which the selector may be set at intervals corresponding to the letter-space movements of the carriage, and a connection between the carriage and the carrier, disconnectible at will to enable the carrier to be moved to a suitable position to permit the selector to be set thereon as desired.

22. In a combined typewriting and computing machine, in combination, a typewriter carriage, a register comprising numeral wheels, actuating means for said wheels, including denominational elements actuatable in accordance with digits indexed thereon, a tappet to select the denominational elements seriatim and shift them to positions

to receive the indexing of digits, a transposition device comprising an endless band having a lower stretch adjacent said denominational elements, and moving in the reverse of the direction of the carriage movement, band-carrying wheels, a driving connection between said carriage and one of said wheels, including a pinion fixed to the wheel and a rack attached to the carriage and normally meshing with the pinion, and means to disconnect said rack and pinion.

23. In a combined typewriting and computing machine, in combination, a typewriter carriage, a register comprising numeral wheels, actuating means for said wheels, including denominational elements actuatable in accordance with digits indexed thereon, a tappet to select the denominational elements seriatim and shift them to positions to receive the indexing of digits, and a transposition device comprising a pinion and a rack shiftable on said carriage into and out of mesh with said pinion.

BURNHAM C. STICKNEY.
